UNITED STATES PATENT OFFICE.

WILLIAM GRUS, JR., OF CHICAGO, ILLINOIS.

OIL-CUP.

1,260,373.

Specification of Letters Patent. Patented Mar. 26, 1918.

Application filed December 6, 1916. Serial No. 135,377.

To all whom it may concern:

Be it known that I, WILLIAM GRUS, Jr., a citizen of the United States, residing at Chicago, in the county of Cook and State 5 of Illinois, have invented certain new and useful Improvements in Oil-Cups, of which the following is a specification.

This invention relates to a device for attachment for admitting oil or inserting oil 10 to a bearing or into any place in which a liquid is used, and although intended principally for use with oil it can of course have a more general application. The principal object of the invention is to provide a new 15 and improved form of oil cup which is simple and inexpensive to construct and effective and efficient in operation.

In the accompanying drawing, Figure 1 is a side elevation with a portion broken 20 away of an oil cup constructed in accordance with the principles of this invention; Fig. 2 is a sectional view taken on the line 2—2 of Fig. 1; Fig. 3 is a sectional view taken on the line 3—3 of Fig. 2; Fig. 4 25 shows the form of a blank from which the cap is made; Fig. 5 is a sectional view of the preferred construction of an oil cup embodying this invention, and Fig. 6 is a sectional view taken on the line 6—6 of Fig. 5.

30 In most of the oil cups of the class to which this invention belongs, that are in use at the present time, there is some deficiency which renders them unfit for continuous service. Frequently the caps are hinged to 35 the body of the oil cup or the cap is slidable relatively to the body uncovering an aperture through which the spout of the oil can may be inserted. Or there is a slide or movable portion in connection with the side or 40 top of the oil cap which when moved uncovers an aperture for the insertion of an oil can spout. All of these constructions are unsatisfactory for the reason that if the cap is hinged the connection is usually of such 45 a flimsy nature that the least pull will tear off the cap, and in the slidable or movable part constructions the least dent or inaccuracy will make it impossible to slide the movable parts, thereby rendering it impossible 50 to open the oil cup for the insertion of oil. If springs are used they frequently do not seat the cap or cover properly which will permit the admission of dirt and grit, thereby decreasing the efficiency of the oil 55 cup, if not actually clogging it. In the

present construction these difficulties are overcome by having a spring which may be compressed a considerable amount, thus allowing the cap to be raised above the body of the oil cup to a considerable distance for 60 the insertion of oil. A spring is provided which tends to seat the cap evenly and firmly so that there is very little opportunity for dirt to get in the cup, and being self closing, it is proof against inattention 65 on the part of the operator.

Referring now more particularly to the drawing, an oil cup body 8, as shown in Figs. 1, 2 and 3, is formed at one end with a threaded portion 9 adjacent which is a 70 hexagonal portion 10 for screwing the body into a threaded aperture. The other end of the body is entirely open with the exception of opposite tongues 11 which are bent inwardly a short distance with extremities 12 75 bent into the body 8.

A cover or cap 13 is formed from a blank, as shown by Fig. 4, comprising a rounded central portion 14 with oppositely extending arms 15. The arms are bent substantially at right angles to the plane of the cap so that they may be inserted in the body 8, as clearly shown in Fig. 3, the edge of the central portion 14 being crimped around the edge 16, as shown in Fig. 3, to 80 form a seat which rests against the open edge of the body 8. The extremities 17 of the arms 15 are bent inwardly and then at right angles, as shown in Figs. 2 and 3, so that when the cap is applied to the body 90 the bent extremities 17 and 11 are opposite each other. Between these extremities a coil spring 18 is inserted which is held in place by the bent extremities tending to hold the cap over and closely against the open 95 end of the body portion 8. The spring is worked in place with the cap partially raised and when in position there is no tendency for it to become dislocated nor to bear unevenly upon the cap. The cap is 100 easily raised for the insertion of oil by grasping the crimped edge 16 at any point, or at opposite points, as the edge of the cap protrudes beyond the body 8.

In the preferred form, as shown by Figs. 105 5 and 6, the body portion 19 of the oil cup is shown to be made of a tubular member which is reduced at one end forming the threaded portion 9' and an intermediate headed portion 10'. A cap 13' is made of 110

a blank similar to that shown in Fig. 4 and the rounded portion of the cap is strengthened by an insert 20 which is crimped and held in place at the edges when the cap is formed. Instead of bending the extremities of the arms 15 and forming tongues on the body portion of the cup in order to hold the spring 18 in place, a pin 21 is attached adjacent the open end of the body 19 and the extremities 15 of the cap member are joined by a pin 22. As shown in Fig. 6, this pin 22 is formed with flattened or upset portions 23 adjacent the ends to prevent the arms 15' from moving inwardly, and the ends of the arms 15' are bent slightly as at 24 so that the heads 25 of the pin 22 will be flush with the outer surface of the arms. This will facilitate the insertion and operation of the cap in the body.

20 One of the principal advantages gained by this construction is that it can be made of thin tubular and sheet material by punch press operations. This makes the construction simple, strong and inexpensive, and one that is not likely to get out of order. The cap is easily raised for the insertion of oil and is held strongly but evenly on the body of the oil cup. The coil spring is not easily displaced and leaves a large central opening for the admission of oil, at the same time permitting the egress of air at the time of filling.

What I claim is:

1. In an oil cup, a receptacle, a non-tilting cover for the receptacle having parallel arms extending into and closely adjacent the sides of the receptacle, and a spring inserted within the receptacle and between the arms tending to hold the cover on the receptacle.

40 2. In an oil cup, the combination with a receptacle open at one end, and a cover therefor having integral guiding arms which extend parallel to each other within and adjacent the walls of the receptacle to prevent the cover from tilting.

3. In an oil cup, a receptacle open at one end, a cover therefor constructed of a single piece of material having parallel arms that extend from opposite sides of the cover and downwardly into and along the sides of the receptacle to prevent tilting, and means for engaging the arms yieldingly holding the cover in place.

55 4. In an oil cup, the combination with a receptacle open at one end, of a cover therefor comprising a flat piece of sheet material having an enlarged central portion and oppositely extending arms, the edges of the central portion being crimped to fit over the end of the receptacle with the arms extending within the receptacle, and means to hold the cover on the receptacle.

5. In an oil cup, an open-ended receptacle, 65 a cover fitting over the open end, with

rigidly attached arms extending within the receptacle close to the sides and on opposite sides thereof, forming a centering guide, and means comprising a spring for yieldingly engaging the arms to hold the cover 70 on the receptacle.

6. In an oil cup, a tubular receptacle reduced and threaded at one end, a cover for the other end formed of a single piece of sheet material having integral portions 75 which extend into the receptacle to guide the cover and prevent it from tilting, and a spring for holding the cover in place.

7. In an oil cup, a tubular member forming a receptacle and reduced and threaded 80 at one end with an intermediate angular portion, a non-tilting cover for the other end having integral arms forming a guide slidable in and close to the wall of the member, and a spring for holding the cover in 85 place.

8. In an oil cup, the combination with a receptacle open at one end, a cover for the open end having integral arms extending close to the wall within the receptacle to 90 prevent tilting, means attached to the receptacle adjacent its open end for engaging one end of the spring, and means at the ends of the said arms for engaging the other end of the spring.

9. In an oil cup, the combination with an open ended receptacle, of a cover therefor formed of a flat piece of sheet material with a large central portion and oppositely extending arms, the central portion being crimped at the edges to bend the arms to extend within the receptacle, the crimped edge abutting the end of the receptacle, and means for yieldingly holding the cover in 100 place.

10. In an oil cup, an open ended tubular receptacle, a cover therefor rounded outwardly from the receptacle with integral parallel arms extending within the receptacle, a reinforcement for the rounded portion of the cover, and means for yieldingly holding the cover on the receptacle.

11. In an oil cup, a receptacle having an open end, a cover therefor having arms extending into the receptacle, on opposite sides 115 forming a guide to prevent tilting, a coil spring insertible within the receptacle, means at the ends of the arms to engage one end of the coil spring, and means adjacent the open end of the receptacle extending 120 transversely of the arms for engaging the other end of the spring.

12. In an oil cup, a receptacle formed of tubular material reduced and threaded at one end and open at the other, a cap for the open end composed of sheet material with integral arms extending into the open end of the receptacle adjacent the sides thereof to prevent tilting, a reinforcement for the cap, a pin connecting the extremities 125

of the arms, a member extending transversely of the arms and attached to the receptacle at the open end, and a coil spring interposed between said member and the pin at the extremities of said arms which tends to hold the cover on the receptacle.

13. In an oil cup, an open ended receptacle; a cover therefor formed of a flat piece of sheet material with a central portion extending over the top of the receptacle and integral arms bent inwardly from the edge of the cover and insertible within the receptacle forming a guide for the cover to

prevent tilting; and means for yieldingly holding the cover in place. 15

14. In an oil cup, an open ended receptacle; a non-tilting cover therefor crimped at the edges to fit over the receptacle, and extending portions to slide within the receptacle; and means for yieldingly engaging 20 said extending portions to hold the cover in place.

In testimony whereof I have signed my name to this specification, on this 29th day of November, A. D. 1916.

WILLIAM GRUS, JR.
